R. TANNENBAUM.

CONCRETE FORM.

APPLICATION FILED NOV. 26, 1919.

1,367,214.

Patented Feb. 1, 1921.

Inventor:

Robert Tannenbaum,

By Arthur S. Ewald,

Attorney.

UNITED STATES PATENT OFFICE.

ROBERT TANNENBAUM, OF CINCINNATI, OHIO.

CONCRETE-FORM.

1,367,214.

Specification of Letters Patent.

Patented Feb. 1, 1921.

Application filed November 26, 1919. Serial No. 340,848.

To all whom it may concern:

Be it known that I, ROBERT TANNENBAUM, a citizen of the United States, and a resident of Cincinnati, in the county of Hamilton 5 and State of Ohio, have invented certain new and useful Improvements in Concrete-Forms, of which the following is a full, clear, and exact description, reference being had to the accompanying drawings, forming a 10 part of this specification.

My invention relates to concrete forms, and has for its principal object the provision of forms for the pouring of concrete in the construction of foundations and other structures, of such a nature that the same may be readily assembled and taken down with a minimum of labor, and which may be used repeatedly without depreciation or injury, materially affecting their availability for 20 the designated purpose.

A further object of the present invention is to provide in concrete forms, separate boards or members having cleats for convenient assembly.

Another object is to provide boards or members for the construction of concrete forms having beveled edges whereby the seepage of concrete is permitted to drain from the edges of the boards, thus obviating 30 the necessity for cleaning the boards after each use.

A still further object of this invention is to provide in a concrete form, constructed of a plurality of boards, expansion members, 35 whereby the expansion or swelling of the boards may be accommodated, and the concrete structure relieved of any strain therefrom.

Another object of the invention is to provide in a concrete form, boards or members, which are adapted for assembly or use as a concrete mixing board.

Further objects of the invention will appear from the following detailed description 45 thereof.

In the drawings:

Figure 1, is a perspective of a portion of a concrete form constructed in accordance with the present invention.

Fig. 2, is a perspective of one of the boards or members.

Fig. 3, is a perspective of one of the expansion members.

Fig. 4, is a perspective of a number of the

form members assembled for use as a mixing board.

The numeral 1 indicates timbers of desired dimensions which are disposed longitudinally in pairs along the sides of the proposed structure, and the intersections spiked together as shown at 2. In order to accommodate the dimensions of the proposed structure, the timbers may be overlapped, if necessary, as shown at the top in Fig. 1. The walls of the form are constructed of 65 form boards or members 3 on the back sides of each of which is a plurality of angularly disposed cleats 4. The cleats 4 are so disposed that either end of the boards or members 3 may be uppermost, and the cleats 70 will overlap the boards and be in contiguous relation to each other as clearly shown in Fig. 1 of the drawings. When assembled, the cleats hold the boards in alinement so that the inner wall 5 composed of the assembled boards, presents a smooth plane surface. The boards are nailed to the longitudinal timbers 1. At suitable intervals, the two 75 walls or sides of the form, are, as is customary, held together by means of wires 6 which are looped about the timbers 1 and extend between contiguous boards of the two walls of the form. The edges 7 of the boards 80 3 are beveled, as shown, to the rear, so that the contacting edges 8 of the boards are 85 relatively sharp, and the boards may thus be compressed tightly against the wires which slightly indent the thin edges 8. To the rear, the adjacent beveled edges 7 of the boards leave a crevice or vertical crack 9 for 90 the purpose hereinafter set forth.

In connection with the members or boards 3, I provide expansion members 10, each comprising a thin front plate 11 made of sheet metal or other suitable material, and 95 a back rib or stiffener 12, secured to the plate 11 by any suitable means. The rib 12 is of the same thickness as the members or boards 3. Pivots secured to the back of the rib 12 is a cleat, or cleats, 13 which is adapted 100 to be rotated to lock the expansion member to boards 3, as shown in Fig. 1 of the drawings, in which position the rib 12 is laterally removed from the members 3 at each side of the expansion member. I employ expansion 105 members on each side of the corner of each wall, as also shown in Fig. 1, for the purpose hereinafter set forth. At 14 in Fig. 1

of the drawings, I have disclosed a window frame positioned in the wall.

The nature and use of the present invention will be clear from the foregoing description. In order to construct a concrete form, the timbers 1 are longitudinally disposed on the sides of the contemplated structure for both inner and outer walls of the form. Between the timbers, the walls of the form are formed by means of members 3 disposed and interlocked by means of cleats 4 as above set forth, the members being also nailed to the timbers. At suitable intervals, wires 6 are used to maintain the two walls of the form in proper relative positions, the wires 6 passing between contiguous boards in the opposite walls, and being looped about the timbers as shown. For this purpose, it is necessary that the joints between boards be approximately opposite and in order to accomplish this, if necessary, one or more expansion members 10 may be employed, as it is obvious that members 3 may be displaced at suitable distances to accomplish this result from the stiffening rib 12 of the expansion members. In order to prevent the cracking of the concrete wall when poured at the corners by the lateral extension of the forms through swellings when they become wet, I also provide expansion members 10 in each wall in each side of the corner. These members permit the boards 3 when expanding, to slide at the rear of the plates 11, as in original placement the edges of the boards 3 are displaced from the ribs 12. This prevents the expansion of the boards from forcing outwardly the concrete of the wall at the corners, and thus prevents cracking. Between contiguous boards, the crevices 9 permit free passage for any seepage downwardly, and it is not caused to adhere to the edges of the boards as is the case where such seepage is compressed between contiguously disposed parallel surfaces. The thin edges 8 also caused by the beveling of the edges of the boards, permit the wires 6 to be embedded in the edges, and thus admit of the contiguous placing of the boards without any cracks or openings between the same. As shown in Fig. 4, furthermore, the members 3 may be assembled for use as a mixing board.

By the use of the members above set forth, concrete forms may be repeatedly assembled and knocked down without destruction or excessive wear on the parts, and for this reason, the parts may be repeatedly used. Furthermore, it will be seen that by the use of members as above described, a minimum amount of labor is required, as in many instances, a single mechanic is enabled to construct or assemble the entire form with great facility, and the same simplicity attends the knocking down of the form.

Having thus fully described my invention,

what I claim as new and desire to secure by Letters Patent, is:—

1. Parts for the construction of concrete forms comprising timbers adapted to be disposed in longitudinal arrangement with reference to a proposed construction, members adapted to be arranged vertically with reference to said construction and to be temporarily nailed to said longitudinal timbers, and cleats on the rear sides of said vertical members to hold the front surfaces of said members in alinement. 70 75

2. Parts for the construction of concrete forms comprising timbers adapted to be disposed in longitudinal arrangement with reference to a proposed construction, members adapted to be arranged vertically with reference to said construction and to be temporarily nailed to said longitudinal timbers, and cleats on the rear sides of said vertical members to hold the front surfaces of said members in alinement, said cleats being angularly disposed so that said vertical members may be assembled without reference to the disposition of the ends of each. 80 85 90

3. Parts for the construction of concrete forms comprising members adapted to be disposed in longitudinal arrangement with reference to a proposed construction, members adapted to be arranged vertically with reference to said construction and to be temporarily secured to said longitudinal members, the edges of said vertical members being beveled to the rear, and cleats on the rear sides of said vertical members to hold the front surfaces of said members in alinement. 95 100

4. Parts for the construction of concrete forms comprising members adapted to be disposed in longitudinal arrangement with reference to a proposed construction, members adapted to be arranged vertically with reference to said construction and to be temporarily secured to said longitudinal members, cleats on the rear sides of said vertical members to hold the front surfaces of 105 110 115 said members in alinement, expansion members, and means for securing said expansion members between vertical members.

5. Parts for the construction of concrete forms comprising members adapted to be disposed in longitudinal arrangement with reference to a proposed construction, members adapted to be arranged vertically with reference to said construction and to be temporarily secured to said longitudinal members, cleats on the rear sides of said vertical members to hold the front surfaces of said members in alinement, said cleats being angularly disposed so that said vertical members may be assembled without reference to 120 125 the disposition of the ends of each, expansion members, and means for securing said expansion members between vertical members.

6. Parts for the construction of concrete 130

forms comprising members adapted to be disposed in longitudinal arrangement with reference to a proposed construction, members adapted to be arranged vertically with reference to said construction and to be temporarily secured to said longitudinal members, the edges of said vertical members be-

ing beveled to the rear, cleats on the rear sides of said vertical members to hold the front surfaces of said members in alinement, 10 expansion members, and means for securing said expansion members between vertical members.

ROBERT TANNENBAUM.
